(Cl. D29—1)

To all whom it may concern:

Be it known that we, Henry C. Muhlenbrook and Joseph Feldman, citizens of the United States of America, residing at Glendale and New York, respectively, in the counties of Queens and New York, respectively, and State of New York, have invented a new, original, and ornamental Design for a Wreath, of which the following is a specification, reference being had to the accompanying drawing, forming part thereof.

In the drawing,

Fig. 1 is a front elevational view of the wreath showing our new design;

Fig. 2 is a side view of Fig. 1.

We claim:

The ornamental design for a wreath, as shown.

HENRY C. MUHLENBROOK.
JOSEPH FELDMAN.
